(57) **CLAIM**

The ornamental design for an ambient lamp, as shown and described.

DESCRIPTION

FIG. 1 is a front elevational view of an ambient lamp showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is a third perspective view thereof;

FIG. 10 is a perspective view in an alternative configuration; and,

FIG. 11 is a second perspective view in an alternative configuration.

The broken lines illustrate portions of the ambient lamp that form no part of the claimed design.
